SHAPING MACHINE FOR GARMENTS

Jesse A. Self, High Point, N. C., assignor of sixty
per cent to D. S. Sherrod, High Point, N. C.

Application January 30, 1940, Serial No. 316,383

4 Claims. (Cl. 223—2)

This invention relates to a garment shaping machine for collars, lapels, cuffs and the like and more especially an apparatus of this type which is wholly or partially operated by pneumatic means.

It is an object of this invention to provide a garment shaping machine comprising a lower die and an upper die, between which a portion of garment upon a form is adapted to be inserted, together with a compressed air unit for applying and relieving the relative pressure between the dies and inserted garment. The compressed air unit has foot operated valves which serve to admit or exhaust air from a suitable die actuating cylinder.

One of the most unusual features of this machine is that enough of the pressure can be relieved from one of the dies to release the form and allow it to be withdrawn, but at the same time, sufficient pressure is retained between the dies to hold the garment in position. After removal of the form the pressure is applied again to set the garment more permanently than could possibly be the case with the pressure applied with the garment on the form.

Some of the objects of the invention having been stated, other objects will appear as the description proceeds, when taken in connection with the accompanying drawings, in which—

Figure 1 is a side elevation of a garment shaping machine embodying an improved pneumatic control unit;

Figure 2 is an enlarged plan view taken along the line 2—2 in Figure 1;

Figure 3 is an isometric view of a portion of a shirt collar which is of a suitable construction to be shaped by the present invention;

Figure 4 is a transverse vertical sectional view taken along line 4—4 in Figure 2, but showing the form and fabric thereon disposed between the dies;

Figure 5 is a sectional view taken along line 5—5 in Figure 1 showing the foot operated pneumatic control mechanism;

Figure 6 is a schematic wiring diagram of the heating unit employed in the invention.

Referring more particularly to the drawings, the numeral 10 denotes a table having a framework 11 mounted thereon, said framework having a horizontally disposed plate 12 and an inclined plate 14 mounted on the upper portion thereof. Plate 14 has lug angles 15 and 16 secured to its lower face, and slidably mounted in these angles are the intermediate portions of inclined rods 17. The upper ends of these rods

extend beyond the downstanding leg of lug angle 15 and have resilient washers 18 mounted therearound, said washers being normally confined on the rods by any suitable means such as a plate 19 which spans the distance between, and is secured to, the extreme upper ends of rods 17. A tension spring 20 has one end thereof secured to the plate 19 and its other end secured to lug angle 16 so as to provide means for normally pulling the rods 17 downwardly or to the position shown in Figure 1.

On the lower end of rods 17, a bracket 25 is secured which in turn, has a base plate 26 mounted on its upper side. The base plate is adapted to have suitable form plates 27 secured to its upper face by any suitable means such as bolts or rivets 28. It will be seen by referring to Figure 2 that the form plates 27 are identical and are shaped so as to fit between the folds of a collar or lapel such as designated by the reference 30. Figure 3 shows a portion of collar 30 and it is here seen that three layers of fabric, namely 31, 32, and 33 are secured together by means of stitches or seams 34. The collar is then inserted upon form plate 27 in the manner shown in Figure 2 with the form disposed between the layers.

After placing the collar points on the forms, it is necessary to move the assembly upwardly to the position shown in Figure 4, between a pair of dies where heat and pressure can be applied. The means for moving the collar points and forms between the dies comprises a cord 37, pulley 38, treadle 39, foot rest 40 and floor bracket 41. In Figure 1 it is seen that one end of the cord is secured to bracket 25 as at point 42, and from this point the cord passes upwardly and over pulley 38, and thence downwardly to the free end of treadle 39. This treadle is pivoted as at 44 to floor bracket 41. Upon application of pressure to this treadle the form plates 27 and the associated rods 17 are caused to move upwardly to the right in Figure 1 against the tension of spring 20 to the position shown in Figure 4. When in this position, the points of collar 30 and form plates 27 are disposed immediately above inclined plate 14 and below die plates 45, the plate 14 serving as a stationary die and the plates 45 serving as movable dies.

In order to limit the upward movement of the form plates 27 and also to vary the point to which these plates may move, a bolt 25a is threadably secured in bracket 25. The head of this bolt is adapted to contact the downstanding leg of lug angle 16 when the form plates are in uppermost position (see Figure 4).

The lower die plate 14 has a plate 46 secured to the upper surface thereof, which plate 46 resembles an inverted W; thereby providing a pair of inverted V-shaped cavities into which the 5 form plates 27 and collar points are inserted. Also the movable die plates 45 are adapted to have vertical movement in these cavities when pressure is applied and relieved to and from the collar points. Die plates 45 are secured to 10 brackets 50 which in turn, are loosely mounted on a shaft 51. The shaft 51 is fixed between the prongs of a Y-shaped yoke 52 and the intermediate portion of this yoke is rotatably mounted on a second shaft 53 which is supported by 15 brackets 54 on lower die plate 14. A rigid hook member 47 is provided for each of the top die plates 45, each of said hook members having slots 47a therein which are penetrated by screws 48 and these screws are threadably secured in yoke 20 52. The hooked end 49 of each of the hooked members 47 is positioned in close proximity to the intermediate portion of a bracket 56 which bracket supports upper die plate 45. The position 25 of the hooked ends relative to the brackets can be varied by loosening the screws 48 so as to permit the slots 47 to be moved relative to the screws. When the die plates 45 are in raised position as shown in Figures 1 and 4, there is practically no stress between the ends 49 and the 30 brackets 56; however when the yoke 52 is rotated in a counter-clockwise manner in Figure 4 to cause the die plates to be moved downwardly to compress the garment therebelow, the ends 49 of the rigid hook members 47 will engage these 35 brackets and thereby force the upper die plates 45 backwardly toward the apices of the inverted V-shaped cavities formed in plate 46.

A bolt 55 is threadably secured in the lower die plate 14 directly beneath yoke 52. This bolt is 40 adjustable as to height and serves to limit the clockwise movement of the yoke 52 about its supporting shaft 53 (Figures 1 and 4) and thereby limits the distance that the movable die plates 45 45 can be withdrawn from the stationary die plate 14. It is evident from the drawings that when the yoke 52 is rotated in a counter-clockwise direction in Figure 4 that the collar points and the forms 27 will be subjected to pressure between the upper and lower dies and upon clockwise rotation of this yoke the pressure between these 50 parts will be relieved.

The uppermost free end of yoke 52 has pivoted thereto as at 57 the upper end of a piston rod 58, said rod extending downwardly into a cylinder 59 and having a piston 60 secured on the lower end thereof. The cylinder 59 is pivoted as at 61 to the framework 11, and this cylinder also has a compression spring 62 on the interior thereof and confined on rod 58 between the upper end of the cylinder and the piston. This spring normally tends to rotate yoke 52 in a clockwise manner (Figures 1 and 4) about shaft 54 to cause the upper and lower die plates to become separated.

The cylinder 59 has an air compartment 65 65 therein immediately below piston 60, said compartment having one end of a conduit 66 communicating therewith, the other end of which communicates with a vertically disposed bore 67 in valve unit 68 (Figures 1 and 5). The bore 67 70 communicates with a restricted bore 70 thereabove and the lower end of this restricted bore is normally closed by a ball 71 which has vertical movement in the bore 67. A compression spring 72 is also disposed in bore 67, the purpose of which 75 being to normally hold ball 71 over the lower end

of bore 70. When air flows from bore 67 to bore 70, it is allowed to exhaust through a port 73.

Another bore 75 leads from bore 67 to a vertically disposed restricted bore 77, said bore 77 being adapted to communicate with an enlarged 5 bore 76 therebelow, in which a ball 78 is disposed. This ball is pressed over the bore 77 by means of a compression spring 79. The bore 76 is connected to a source of compressed air 80 by any suitable means such as conduit 81 (Figure 1). 10

It will be noted by referring to Figures 1 and 5 that the lower end of a vertically disposed pin 82 is disposed in bore 77 and is normally resting on top of ball 78. The intermediate portion of this pin is slidably mounted in the valve unit block 15 and its upper end is adapted to support a treadle 84, which treadle is pivoted as at 85 to the valve unit block. When it is desired to allow compressed air to flow from tank 80 into compartment 65 of cylinder 59, it is only necessary to 20 apply pressure to the free end of treadle 84, which in turn, will move pin 82 downwardly to unseat ball 78 and allow the air to flow through the valve unit 68 into the cylinder 59.

The valve unit 68 also has a treadle 87 pivoted 25 thereto as at 85. The free end of this treadle is normally supported by a pin 88, the lower end of which is disposed in bore 70 and upon ball 71. When it is desired to exhaust the air from compartment 65, it is necessary to apply pressure to 30 treadle 87 which pressure will unseat ball 71 and allow the air within compartment 65 to flow through valve unit 68 and out through exhaust port 73.

In order to provide the necessary heat for the 35 die plates 14 and 45, a heating unit 89 is provided directly below plate 14. This unit has electric wires 90 and 91 leading thereto said wire 90 having a switch 92 therein (Figures 1 and 6). A parallel circuit 93 connects wires 90 and 91, said circuit having an indicating light 94 therein, which serves to indicate, when lit, that current is being admitted to the heating unit 89.

When the machine is in operation, a collar point is placed on each of the plate forms 27 in 45 the manner shown in Figure 2. Then pressure is applied to treadle 39 to cause the forms on collar points to move between dies 14 and 45 as shown in Figure 4. At this time the treadle 84 of valve unit 68 is compressed to allow air to flow 50 into compartment 65 of cylinder 59 and this air will rotate yoke 52 in a counter-clockwise manner (Figures 1 and 4) to cause the upper die plates 45 to apply pressure to both the form plates and the collar points to perform an initial 55 shaping operation on the collar points. Upon applying this initial pressure, the heated dies will slightly cohere to the surface of the dampened collar points; consequently, it will then be possible to partially relieve the pressure between the 60 die plates sufficiently to withdraw the form plates 27, but at the same time will allow the collar points to remain intact with the die plates. This partial release of pressure is a delicate operation, because if too much pressure is released, 65 the collar points will also be withdrawn along with the form plates. For this reason compressed air is highly desirable, because the treadle 87 can be actuated so as to allow the exact quantity of air to be released in order that 70 a corresponding reduction in pressure between the die plates can be effected and the reduced pressure held at that point. If manually operated release means is used instead of pneumatic means as disclosed, the operation is not satisfac- 75

tory on account of the lack of control of the pressure between the die plates.

After the forms 27 have been withdrawn, the operator again applies pressure on treadle 84 to cause the maximum pressure to be exerted by the dies upon the collar points therebetween. When the points have been properly shaped, the pressure is then released and the parts are returned to normal position for the next operation.

10 In the drawings and specification there has been set forth a preferred embodiment of the invention, and although specific terms are employed, they are used in a generic and descriptive sense only and not for purposes of limitation, the 15 scope of the invention being set forth in the appended claims.

I claim:

1. A garment shaping machine comprising a stationary die and a relatively movable die, a 20 movable form, foot operated means for inserting the form with a garment thereon between said dies, a lever pivoted intermediate its ends and having said movable die secured on one end thereof, a piston secured to the other 25 end of said lever, a cylinder for slidably enclosing said piston, other foot operated means adjacent the first foot operated means for introducing air into said cylinder whereby said lever will be actuated to cause the movable die to move toward 30 this stationary die, and a pair of rigid hooked members carried by said lever for normally forcing the upper die plate rearwardly of said machine and against the sidewalls of the lower die upon introduction of air into said cylinder.

35 2. A garment shaping machine comprising a pair of dies relatively movable toward and away from each other, said upper die being supported by a lever, a movable form, a foot lever for moving the form with a garment thereon between 40 said dies, pneumatic means for varying the amount of pressure between said dies when the garment and form are disposed therebetween, a pair of other foot operated levers adjacent the first foot lever for controlling the pneumatic

means, a pair of rigid hooked members carried by said lever for normally forcing the upper die plate rearwardly of said machine and against the sidewalls of the lower die upon introduction of air into said cylinder.

3. A garment shaping machine, comprising in combination, a lower die having a recess therein having a point for shaping a point of a garment, an upper die cooperating with said lower die and mounted in said recess, a shaft mounted adjacent said lower die and located substantially above the point of said recess, a yoke pivotally mounted on said shaft, pivotal connections between said upper die and said yoke located on the same side of said shaft as said upper die and 15 a rigid stop carried by said yoke, said stop being adapted to engage the upper die upon downward movement of the same to force said upper die toward the point of said recess.

4. A garment-shaping machine comprising, in 20 combination, a lower die having a pointed recess therein suitable for receiving a pointed portion of a garment, a pivot mounted on said lower die and extending transversely of the point of said recess, a lever mounted on said pivot and having 25 an end overlying said recess, an upper die of suitable shape to enter said recess and compress the point of a garment in said recess, said upper die being pivotally mounted on said overlying end of said lever and being unguided except by the 30 walls of said recess and by said pivot between said upper die and its supporting lever, a stop carried by said lever, said stop being adapted to engage the upper die upon downward movement of the same to force said upper die toward the 35 point of said recess, a form for carrying the garment and being movable to a position between the upper and lower dies, a foot lever for moving the form, pneumatic means for lowering and raising the upper die, and a pair of pedals engageable by the foot which operates the pedal for moving the form, for controlling the movements of the upper die.

JESSE A. SELF.
